ATTORNEYS.

UNITED STATES PATENT OFFICE.

FRANK CROSSMAN, OF SAN FRANCISCO, CALIFORNIA.

PORTABLE BURGLAR ALARM.

Application filed August 16, 1921. Serial No. 492,770.

To all whom it may concern:

Be it known that I, FRANK CROSSMAN, a citizen of the United States, and resident of San Francisco, county of San Francisco, 5 and State of California, have invented a new and useful Portable Burglar Alarm, of which the following is a specification.

The present invention relates to improvements in burglar alarms and its specific object is to provide a burglar alarm that can be conveniently carried in a suit case, can be quickly attached to any door knob and sounds the alarm when the door knob is turned in either direction. It is principally 10 intended for travellers who frequently change their quarters and have to sleep in places not familiar to them, and provides for them a convenient means of apprising them of any attempt to open the door.

20 The preferred embodiment of the principles involved in my invention is shown in the accompanying drawing, which represents a front elevation of my device attached to a door knob.

25 Referring to the drawing in detail, I wish to state that the principle involved in my invention is the use of an electric alarm unit pivotally depending from the door knob in such manner that it maintains its perpendicular position underneath the door knob although the latter is turned, whereby a metallic part of the device is brought in contact with the door knob and closes an electric circuit, which sounds the alarm.

30 35 The door (1), of which only a fragment is shown in the drawings, has the door knob (2) attached thereto as in any ordinary door. It is understood that this door knob has to be revolved in order to open the door. To the latter my electric alarm device (3) is attached by means of the clamp (4). Various fastening means may be used 40 as long as they properly perform the function stated herein. The special clamp 45 shown consists of two metallic semi-circular members (6) adapted to fit around the knob of the ordinary door and to be tightened on the same by means of the screws (7) having milled heads (8) and penetrating perforations (9) in flanges (11) of one of the members and adapted to be screwed into nuts (12) fixedly secured to registering flanges of the other member. The clamp members are provided with peripheral flanges (14) 55 to insure a more perfect clamping effect.

From a central portion of the lower

clamping member depend two parallel lips (16) having registering perforations and being adapted to receive a perforated projection (18) made of insulating material, of 60 the electric alarm device (3). A screw (19) extending through the perforations allows the bell arrangement to freely swing on the pivot parallel to the door.

The alarm device, which is not shown in detail, may be of any desired form and includes the two batteries (21), a bell (22), a bell hammer (23) and preferably an electromagnet, an armature and a vibrator. The wiring is easily understood. The circuit 70 leads from the terminal (24) of one of the batteries to the contact (26), from there through the electromagnet and through the contact spring and contact point not shown in the drawing to the contact (27) and 75 through the wire (28) to the metallic clamp (6) which is electrically separated from the alarm device through the insulating projection (18). The terminal of opposite character of the other battery is connected, 80 preferably by a spring not shown, to the metal plate (29) lying across the two batteries from which rise two metal screws (31) in spaced relation. The screws can be screwed into their support whereby their 85 length above the batteries is adjusted and can be secured in their adjusted position by the nuts (32). They are so positioned relative to the door knob that a turning of the knob will bring one or the other of them into 90 contact with the clamps and thereby close the circuit which causes the bell to ring.

The use of my device is easily explained. To fasten it to a door knob place the clamps around the same and tighten the screws (7), at the same time clamping the end of the wire (28) between the door knob and the clamp. If anybody now tries to open the door by turning the door knob the alarm device will remain in its perpendicular position but will be raised and moved laterally on account of the fact that its supporting pivot (19) is raised and moved laterally, and this motion will bring one of the screws (31) in contact with the clamp, whereby 105 the bell actuating circuit is closed, the current flowing from the battery terminal (24) through the bell actuating device to the contact at (27), from there through the wire (28) to the clamp and from there through 110 one of the screw contacts to the plate (29) and the terminal of the other battery.

It is understood that, as above stated, the main feature of my device is the use of the revolving knob for sounding the alarm, and this can probably be effected by use of other than electric means, without affecting the spirit of my invention.

I claim:

In combination with a revolvable knob, a burglar alarm comprising an electric ringing device, a source of electrical energy, a metallic clamp secured on the knob having means thereon for pivotally supporting the

device, means for insulating the clamp from the latter, a metallic connection between said source and the clamp passing through the ringing device, two lateral contacts rising from the latter and extending to within close proximity of the clamp on opposite sides being electrically connected with the source of energy and adapted to engage the clamp when the knob is turned for ringing the bell.

FRANK CROSSMAN.
